UNITED STATES PATENT OFFICE.

THOMAS DOUGHERTY, OF MINNEAPOLIS, MINNESOTA.

RAIL-JOINT.

1,383,086.

Specification of Letters Patent. Patented June 28, 1921.

Application filed October 2, 1920. Serial No. 414,365.

To all whom it may concern:

Be it known that I, THOMAS DOUGHERTY, a citizen of the United States, residing at Minneapolis, in the county of Hennepin 5 and State of Minnesota, have invented new and useful Improvements in Rail-Joints, of which the following is a specification.

My invention relates to rail joints and has for its object to provide a rail joint 10 which will firmly clamp the ends of the two rails together so as to prevent relative, lateral movement of the ends of the rail and still allow the rails to expand and contract without affecting the rigidity of the 15 connection. In carrying out my invention I provide two members which are bolted on both sides of the rails between the head and the base and have tapered sockets fitting around the base of the rail. These members 20 are further provided with flanges extending below the rail base which assist in clamping the joint around the rail base.

The full objects and advantages of my 25 invention will be found in connection with the detailed description thereof and are particularly pointed out in the claims.

In the drawings, illustrating my invention in one form: Figure 1 is a side view of a pair of rails showing my invention applied 30 thereto. Fig. 2 is a plan view of the rails and joint shown in Fig. 1. Fig. 3 is a view similar to Fig. 2 taken from the bottom looking up. Fig. 4 is a sectional view taken on line 4—4 of Fig. 1. Fig. 5 is a sectional view 35 taken on line 5—5 of Fig. 1.

My invention as is best shown in Figs. 1 and 2, is shown attached to the ends of two rails 10 and 11 which are of the usual design having heads 14 and 15, webs 16 and 17 40 and the bases 18 and 19 which rest on ties 20 and 21 of standard size and spaced the customary distance apart. My rail joint comprises two castings or drop forgings 12 and 13 which have longitudinal web portions 45 22 and 23 which extend along the rails 10 and 11 between the heads 14 and 15 and the bases 18 and 19 thereof. At the lower portions of the members 12 and 13, the metal follows along the tops of the rail bases as 50 indicated at 24 and 25 extending throughout the entire length of the joint. Between the ties 20 and 21 portions 26 and 27 of members 12 and 13 are formed, which extend on the underside of the bases 18 and 19 of the rails 55 10 and 11, and terminate in downwardly ex-

tending flanges 28 and 29. The proportions of the parts and the manner in which they fit around the rail are clearly shown in Fig. 4.

The manner of fastening the joint to the 60 rail is as follows: Four track bolts 30, 31, 32 and 33 pass through the web portions 16 and 17 of the rail ends, as in ordinary rail joints. The holes are drilled and spaced according to the standards of track practice 65 so that an ordinary rail joint may be removed and my improved joint substituted for it without any alterations to the existing track. In addition to these bolts the rail joint is further held together by two track 70 bolts 34 and 35 which pass through the flanges 28 and 29 immediately below the rail bases 18 and 19 and the portions 26 and 27 of the joint proper.

In applying the joint to the rails, bolts 30, 75 31, 32 and 33 are first tightened up. This throws a shoulder 36 formed on the upper portion of each of the members 22 and 23 against the webs 16 and 17 immediately below the rail heads 14 and 15. It will be 80 noted in Fig. 4 that gaps 41 and 42 are left between the rail heads 14 and 15 and the shoulders 36 to make sure that these shoulders will engage the webs 16 and 17 and not the under side of the rail heads. At the 85 same time portions 24 and 25 and 26 and 27 are forced in contact with the rail bases 18 and 19. To insure contact with these rail bases in the proximity of the rail webs, two elongated pockets or recesses 37 and 38 are 90 formed in members 12 and 13 at the junctions of the portions 24 and 26 and 25 and 27 which prevent the extreme outer edges of the rail bases from engaging the rail joint members and so preventing further movement of these members toward each other in the event that portions 24, 25, 26 and 27 do not engage the rail bases near the webs. After bolts 30, 31, 32 and 33 have been sufficiently tightened up, the two remaining bolts 95 34 and 35 are tightened. This has the effect of throwing the corners 39 and 40 of members 12 and 13 against the lower surfaces of the rail bases 18 and 19, thus firmly clamping the joint to the rails. A space 45 is left 100 between flanges 28 and 29, to prevent termination of movement of these members toward each other prior to the engagement of portions 24, 26, 25 and 27 with the rail bases 18 and 19. Any bending at the junction of 105

110

members 26 and 28 and members 27 and 29 is prevented by two transverse webs, 43 and 44 formed integral with the structure.

The rails are fastened to the ties 20 and 21 adjacent the joint in a manner best shown in Figs. 3 and 5. Beyond the flanges 28 and 29 portions 24 and 25 of the rail joint do not return under the rail bases but terminate in ears or lugs 46, 47, 48 and 49 which project 10 out beyond the rest of the rail joint and lie flush with the bottom of the rail bases. These lugs form a seat for the joint on the ties 20 and 21 and are each provided with a notch 50 by means of which the rails 15 and joint are spiked to said ties through spikes 51.

The advantages of my invention are manifest. A perfectly rigid connection is secured, by preventing vertical bending 20 through the clamping of the rail bases and relative lateral movement of the rails by the clamping of the rail webs near the heads. Inasmuch as the size of the bolt holes does not affect the utility of the joint the same 25 can be made large enough so that expansion and contraction of the rails can be taken care of without sacrificing in the rigidity of the connection. The joint can be applied to the rails without re-drilling or moving the 30 ties and can be installed as quickly as any of the ordinary types of rail joints.

I claim:

1. A rail joint comprising a pair of longitudinal members each having a portion 35 directly engaging and clamping the webs of the rails immediately below the rail heads, said portion operating free of the rail heads, a V shaped portion adapted to engage the sides of the rail base operating free of the 40 rail web, means for drawing said first named portions together and means for drawing said V shaped portions together.

2. A rail joint comprising a pair of longitudinal members, each having a beaded head 45 directly engaging the rail webs immediately below the rail heads and operating free from the rail heads and from the rail web below the engagement therewith, a depending ver-

tical body portion connected with said beaded head, an inclined slidable portion issuing 50 angularly outwardly from said body portion and engaging the upper surface of the rail base throughout its length, said angular portion operating free of the web at its junction with the base and operating free of the 55 extreme edge of the base of the rail, a base portion yieldingly connected to said angular portion and extending inwardly therefrom on the underside of the rail, a bracket depending from said base portion, bracing 60 means for rigidly connecting said bracket to said base portion, means for drawing said body portions together to cause the beaded heads thereof to engage the rail web and draw the rail head gage surfaces in alignment, and means for simultaneously drawing 65 said angular and base portions inwardly upon the base and for bending the said base portion upwardly from its yieldable connection with said inclined portion so as to cause 70 the inner corners thereof to engage the lower portion of the rail base and force the upper surfaces of the rail heads in alignment.

3. A rail joint comprising a pair of longitudinal members each having a portion directly engaging the rail webs immediately 75 below the heads, said portions operating free of the rail heads, a portion slidable on the upper surface of the rail base operating free of the edge of said base and the rail webs, a second portion yieldingly connected to said first named base portion extending to the underside of said rail base, a bracket depending from said last named base portion, means for rigidly bracing said bracket 80 to said last named portion, means for drawing said first named portions together to freely clamp the rail webs and means for simultaneously drawing said upper and lower base engaging portions upon said base and 85 for bending said lower base engaging portion upon its yielding connection with said upper base engaging portion against the underside of the rail base.

THOMAS DOUGHERTY.
